US0D1031828S

(12) **United States Design Patent** (10) **Patent No.:** **US D1,031,828 S**
(45) **Date of Patent:** **** Jun. 18, 2024**

(54) **PRINTER**

(71) Applicant: **BROTHER INDUSTRIES, LTD.**,
Nagoya (JP)

(72) Inventor: **Takaaki Oguchi**, Nagoya (JP)

(73) Assignee: **BROTHER INDUSTRIES, LTD.**,
Nagoya (JP)

(**) Term: **15 Years**

(21) Appl. No.: **29/888,372**

(22) Filed: **Mar. 30, 2023**

(30) **Foreign Application Priority Data**

Feb. 7, 2023 (JP) ..... 2023-002143 D

(57) **CLAIM**

The ornamental design for a printer, as shown and described.

DESCRIPTION

FIG. 1 is a perspective view of the printer;
FIG. 2 is a front elevational view thereof;

FIG. 3 is a rear elevational view thereof;

FIG. 4 is a left-side elevational view thereof;

FIG. 5 is a right-side elevational view thereof;

FIG. 6 is a top plan view thereof; and,

FIG. 7 is a bottom plan view thereof.

The evenly spaced broken lines depict unclaimed parts of the printer and form no part of the claimed design.

1 Claim, 7 Drawing Sheets
